UNITED STATES PATENT OFFICE

ALVA L. KERR, OF MANSFIELD, OHIO

LATCHING MECHANISM

Application filed September 21, 1932. Serial No. 634,241.

This invention relates to a latching mechanism which is mainly intended for heavy doors, such as the doors of office buildings, hospitals and various types of public buildings, where stiff door checks or snubbers are used to keep the doors tightly closed until the latch has first opened and after which a fairly stiff pull is required to open the door.

The general object of the invention is to provide a new type of latch mechanism which can be operated from one side by a simple pull on a handle and from the opposite side by a push on another handle.

This invention also consists in certain other features of construction and in the combination and arrangement of the several parts to be hereinafter fully described, illustrated in the accompanying drawings and specifically pointed out in the appended claims.

20 In describing the invention in detail, reference will be had to the accompanying drawings wherein like characters denote like or corresponding parts throughout the several views, and in which:—

25 Figure 1 is an edge view, with parts in section of the invention, as the same would be applied to a door.

Fig. 2 is a section on line 2—2 of Fig. 1.

Fig. 3 is a top plan view of one of the 30 handles and one of the plates.

In these drawings, the numeral 1 indicates a pair of plates which are adapted to be fastened at the opposite sides of the door or the like, and each plate has the ears 2 on its exterior face between which passes the substantially horizontal part 3 of a substantially L-shaped handle 4, the major portion of which depends from the part 3 as shown. The part 3 is pivoted between the ears as shown at 5, and an inner section 6 is adjustably connected to the inner end 3 by the screw and slot connections shown generally at 7. This permits the part 6 to be removed and also adjusted lengthwise so that the device 45 can be used on doors of different thicknesses.

The inner end of the part 6 is formed with the teeth 8 and with an upstanding head part 9. A pinion 10 is located in the casing 11 into which the parts 6 extend from opposite sides 50 as shown in Fig. 1. This pinion is arranged

between the tooth portions of the two parts 6 and the teeth engage the teeth of the two parts as also shown in Fig. 1.

A lever 12 has an offset, cam-shaped upper end through which a set screw 13 is threaded, the lever normally held against a stop 14 by a spring 15, as shown in Fig. 2. A set screw 16 is carried by the lower end of the lever and engages a slot 17 in the latch or bolt member 18. A spring 19 in the top of the casing bears against the heads 9, retaining an equalized tension on same at all times.

A set screw 20 may be threaded in either side of the casing or housing 11 and acts to limit the drop of that part 6 with which it is associated though permitting upward movement of said part 6. By making this set screw interchangeable from left or right side of the housing and by providing the set screws 13 and 16, the mechanism can be used 70 for either right or left hand doors as the set screw 13 keeps the cam lever 12 at the proper side of the housing and the set screw 16 serves the same purpose and also guides and draws the latch bolt under the action of the lever 12. 75

Thus it will be seen that movement of one handle 4 is imparted to the other handle by the pinions so that a pull on one handle will cause the pinion to raise the head of the other handle and cause said head to swing the lever 12 to move the latch bolt 18 to released position. A push on the handle will cause its head to operate the lever to move the latch bolt to released position.

Thus when one is entering a door which opens from him, regardless of whether the door is hinged at the right or the left, as one faces it, a simple push upon the handle unlatches the door, and that same push continued, opens the door, while in entering the same door from the opposite side, in which case the door must swing toward one, a simple pull unlatches the door and opens it.

The pinion is fixed so that it can neither move up nor down and from this it is readily seen that when one set of teeth move upward, the pinion rolls thus forcing the opposite set of teeth downward, and in like manner, if this downward set of teeth is moved downward first, the pinion rolls thus forcing the 100

opposite set of teeth upward. The reason for making this device for either right or left doors is so that the same lock can be used whether the customer wishes to hinge his 5 door at the right or at the left as he faces same.

It will of course be understood that a lock of cylindrical type can be used with the mechanism if desired.

10 It is thought from the foregoing description that the advantages and novel features of the invention will be readily apparent.

It is to be understood that changes may be made in the construction and in the combination 15 and arrangement of the several parts provided that such changes fall within the scope of the appended claims.

Having thus described my invention, what I claim as new is:—

20 1. Latching mechanism of the class described comprising a housing, a latch bolt having a portion located therein, a lever having an offset upper end of cam shape located in the housing, a pin and slot connection between the bolt and the lower end of the lever, a pair of oppositely arranged handle members having portions entering the housing, said portions having toothed ends, a pinion located in the housing and arranged between 25 said ends and engaging the teeth thereof, each of said handle parts having a head portion for engaging the cam end of the lever for swinging the same when the head part is raised to move the latch bolt to released position, and a spring for normally holding the 30 lever in a position with the latch bolt projected.

35 2. Latch mechanism of the class described comprising a housing, a latch bolt having a portion located therein, a lever having an offset upper end of cam shape located in the housing, a pin and slot connection between the bolt and the lower end of the lever, a pair of 40 oppositely arranged handle members having portions entering the housing, said portions having toothed ends, a pinion located in the housing and arranged between said ends and engaging the teeth thereof, each of said handle parts having a head portion for engaging the cam end of the lever for swinging the 45 same when the hand part is raised to move the latch bolt to released position, a spring for normally holding the lever in a position with the latch bolt projected, means for adjusting the parts for right or left hand doors, means for adjusting the inner end portion of the handle part for different thicknesses of 50 doors, and a spring in the housing engaging the upper ends of the handle parts for retaining an equalized tension on the handle parts 55 at all times.

60 In testimony whereof I affix my signature.

ALVA L. KERR.
